FIG. 1

FIG. 2

Herman L. Brooks

INVENTOR.

UNITED STATES PATENT OFFICE

121,948

DESIGN FOR A JUG

Herman L. Brooks, New York, N. Y., assignor to Coty, Inc., Wilmington, Del., a corporation of Delaware

Application May 15, 1940, Serial No. 92,388

Term of patent 14 years

To all whom it may concern:

Be it known that I, Herman L. Brooks, a citizen of the United States, residing in the city and State of New York, have invented a new, original, and ornamental Design for a Jug, of which the following is a specification, reference being had to the accompanying drawing, forming a part thereof.

In the drawing:

showing my new design.

I claim:

The ornamental design for a jug, substantially as shown.

HERMAN L. BROOKS.
